INVENTOR.

UNITED STATES PATENT OFFICE

JOHN SKOWRON, OF LOS ANGELES, CALIFORNIA

FILING CABINET

Application filed April 4, 1927. Serial No. 180,967.

My invention relates to improvements in filing cabinets, in which the combination of a slotted support and a set of indexed partitions vertically placed in the slotted support, forms a set of adjustable separate compartments for filing papers on different subjects separately and in vertical position.

The principal objects of my invention are, first, to provide a filing cabinet having convenient and adjustable compartments for the vertical filing of papers on different subjects, separately; second, to provide a set of about twenty-six movable partitions which form the compartments and said compartments being easily adjusted by moving the partitions from one point to another as needed according to the number of papers they contain; third, to provide an extension on the upper part of each partition with an alphabetical letter printed on said extension as an index; fourth, to provide front and top covers, which are folded on the back of the cabinet when opened thus giving convenient access to the filing cabinet; fifth, to provide a drawer for small articles such as pencils, stamps, etc. said drawer being provided with a lock on the front inner side to lock the cabinet and the drawer at the same time; and sixth, to provide a filing cabinet of the character referred to that is simple in construction, inexpensive, strong, durable and especially adapted for the purpose for which it is designed.

Other objects and advantages of the invention will become apparent during the reading of the following description:

In the accompanying drawing forming a part of this specification and in which like numerals designate like parts throughout the several views.

Fig. 1 is an isometric view of the slotted supporting member, which comprises a vertical and horizontal wall.

Fig. 2 is an end view of the slotted support.

Fig. 3 is an isometric view of the filing cabinet complete, with cover folded back.

Fig. 4 is a sectional view of a strip of molding.

Fig. 5 is a side view of one of the movable

Referring by numerals to the accompanying drawings, 1 designates the vertical wall and 2, the horizontal wall of the slotted support; said walls having a square angle at the line of fold 3.

Along the top edge of wall 1 at 4, there is a series of slots about one hundred in number, said slots being of uniform size and shape and opening at the top edge.

In the intermediate portion of the horizontal wall at 5 there is a series or row of slots from front to back. The slots in the two above-mentioned walls are equally spaced and correspond in line with each other.

The slotted support Fig. 1 is firmly secured to the inner sides of the three stationary walls as seen in Fig. 3. 7 is the back wall, 6, 6 are the side walls, 13 is the drawer, 14 is the knob on the drawer, 8, the hinge for the cover at the upper edge of the back wall, 9 the hinge between the top and front cover members, 10, the top cover and 11, the front cover. The front cover is shown as being folded over the top cover and both hang on the back when the cabinet is open.

The vertical wall 1 which is placed adjacent to the back wall 7, has its top edge considerably below the hinge 8, and the horizontal wall 2 forms the floor of the filing cabinet.

The knob 14 on the drawer has a keyhole at its center leading to a lock which is secured back of the knob. 15 is a cross-section of a molding in which groove 16 is provided for the drawer to slide.

The moldings 15 are firmly secured by a suitable means, one to each end of the wall 2 on its underneath side and to the inner side of the side walls 6, 6 as shown by the dotted lines at 12 and 23.

The moldings 15 support the wall 2, keep the walls 6, 6 in a firm position and permit the drawer to slide in the groove 16.

Dotted line 23 shows the end of the wall 2 secured firmly against one of the side walls 6, 6. 17 is the indexed partition which has rear and bottom extensions at 18 and 19; said extensions 18 and 19 are all uniform and correspond in dimension and location to the

slots 4 and 5 so that when the extension 18 is placed or inserted in the slot at 4, then the extension 19 enters the proper slot at 5.

The upper extension 20 of the partition 17 is a tab for an alphabetical letter, which serves as an index.

The partition 17 on the drawing shows the first alphabetical letter at 20 and the rest of the partitions of the set have their consecutive letters one after another up to z.

10 A full set of about twenty-six indexed partitions 17 are furnished with each filing cabinet.

15 Insertion of the partitions in the slots is accomplished in the following manner.

Place the extension 18 above the slot 4 and push it down, and while it is moving down the extension 19 drops into its proper slot 5.

20 The partitions 17 have a cut-away space at 21 for the fingers to take hold of the papers.

22 is a slot in the drawer front to admit a catch of the front cover. Suitable means are provided to lock the cabinet and the drawer at the same time at the slot 22, which 25 locks without key and opens with key.

While I have shown the preferred embodiment of my invention it is to be understood that various changes in the size, form and construction of the various parts of my improved filing cabinet may be made and substituted for those herein shown and described without departing from the spirit of the invention, the scope of which is set forth in the appended claims.

35 What I claim is:

1. In a filing cabinet, a slotted device having a vertical and horizontal wall, said slotted device being provided in the upper portion of its vertical wall with a series of slots and 40 in the intermediate portion of its horizontal wall with a row of corresponding slots, a set of partitions adapted to be positioned vertically on said slotted device, and the rear and lower edges of said partitions being provided 45 with projecting portions that are adapted to enter the slots in the vertical and horizontal wall of said slotted device.

2. In a filing cabinet, a slotted device having a vertical and horizontal wall, said slotted 50 device being provided in the upper portions of its vertical wall with a series of slots and in the intermediate portion of its horizontal wall with a row of corresponding slots, a set of partitions, adapted to be positioned vertically on said slotted device, the rear and lower edges of said partitions being provided 55 with projecting portions that are adapted to enter the slots in the vertical and horizontal wall of said slotted device and each partition 60 being provided on its upper edge with an upwardly projecting index-bearing portion.

3. In a filing cabinet, a slotted device having a vertical and horizontal wall, said slotted device being provided in the upper portion of 65 its vertical wall with a series of slots and in

the intermediate portion of its horizontal wall with a row of corresponding slots, a set of partitions adapted to be positioned vertically on said slotted device, the rear and lower edges of said partitions being provided with 70 projecting portions that are adapted to enter the slots in the vertical and horizontal wall of said slotted device, each partition being provided on its upper edge with an upwardly projecting index bearing portion, the lower front corner of each partition being cut away to provide a thumb and finger clearance space.

4. In a filing cabinet, a container having a rear and side walls, a top hinged to the upper edge of the rear wall, a front wall hinged to the front edge of the top, a slotted device positioned within said container, and provided in its vertical and horizontal walls with slots, partitions adapted to be arranged within the container on said slotted device, 80 extensions on said partitions for engaging in the slots in the vertical and horizontal walls of said slotted device, an upward extension on the upper edge of each of said partitions, forming an index-bearing portion and the 85 front corners of said partitions being cut away to provide thumb and finger clearance space.

5. In a filing cabinet, a container having a rear and side walls, a top hinged to the upper edge of the rear wall, a front wall hinged to the front edge of the top, a slotted device positioned within said container, and provided in its vertical and horizontal walls with slots, partitions adapted to be arranged 90 within the container on said slotted device, extensions on said partitions for engaging in the slots in the vertical and horizontal walls of said slotted device, an upward extension on the upper edge of each of said partitions, forming an index bearing portion, the front corners of said partitions being cut away to provide thumb and finger clearance space and in combination with the container a drawer 95 arranged for sliding movement in the lower portion of the container below the horizontal wall of said slotted device.

JOHN SKOWRON.
